APPARATUS FOR CLEANING PIPE SYSTEMS

William J. Kelling, 901 S. Broadway,
Spring Valley, Minn.

Filed Mar. 26, 1963, Ser. No. 268,179

1 Claim. (Cl. 137—209)

This invention relates to methods for cleaning water pipe systems and to apparatus used in such methods.

The art has long experienced the problem of water pipe systems in buildings gradually becoming filled with sedimentation and deposits originating from and associated with the water source used. Aside from the expedient of simply replacing the entire piping system, no practical method and apparatus for cleaning pipe systems is known to me enabling one to extend useful pipe life and improve system capacity to deliver clean, fresh water in abundance. While it has heretofore been proposed to use compressed air in combination with a cleaning liquid, such techniques have suffered from one or more disadvantages such as excessive pipe vibration, excessive consumption of cleaning liquids, and the like.

It is therefore a principal object of this invention to provide a simple, effective, practical method and apparatus for cleaning water pipe systems in buildings.

It is another object of this invention to provide a method and apparatus employing compressed air for cleaning the waterpipes of a water delivery system in a building.

It is another object of this invention to provide a process for cleaning the interior of a water pipe delivery system involving the steps of admitting a liquid cleaning solution to the source pipe of this system from which the water has been drained and thereafter applying sufficient pneumatic pressure to force portions thereof throughout the system and out the faucets.

It is another object of this invention to provide a refillable cartridge for use in the foregoing described process.

It is another object of this invention to provide a refillable cartridge having in its upper end portion of a plug-equipped liquid inlet opening and a valve-equipped air inlet tube and having its lower end portion tapered to a relatively restricted portion which communicates with a normally extending tube through a plurality of longitudinally spaced apertures, said tube being adapted for connection with the source pipe of a water delivery system.

Other and further objects of this invention will be apparent to those skilled in the art.

The invention is further described in the following specification taken together with the drawings in which:

FIG. 1 is an end elevational view of a cartridge constructed in accordance with the invention;

FIG. 2 is a top plan view of the apparatus shown in FIG. 1, some portions thereof broken away;

FIG. 3 is a side elevational view of the apparatus shown in FIG. 1, some portions thereof broken away and some parts shown in section;

FIG. 4 is a schematic view of a water system incorporating my invention; and

FIG. 5 is a flow diagram giving the steps of operation.

Turning to the figures, there is seen in FIGS. 1-3 an embodiment of a refillable cartridge 10 of the invention having a removable plug 11 threaded into the opening in its restricted upper end portion 12. The opening serves to admit cleaning solution 9 to the cartridge 10. The lower end region 13 of the cartridge 10 is tapered. This tapered portion 13 joins with a tube 14 whose axis extends normally to the axis of the cartridge 10. The interior of the cartridge 10 communicates with the interior of tube 14 through a plurality of longitudinally spaced apertures 16. The diameter of each aperture 16 is very much smaller than the diameter of tube 14. Adjacent its upper

2

end, the cartridge 10 is fitted with an air inlet tube 17 whose outer end is threaded to receive a valve 21. In practice, the cartridge 10 and tubes 14 and 17 are formed of metal or plastic. The opposite ends of the tube 14 extend beyond the cartridge 10 and each end is threaded. One end of the tube 14 is fitted with a cap 18, and the other end of the tube 14 is fitted with a valve 19.

The practice of this invention is readily understood by reference to the flow sheet in the drawings. The source of cold water for a cold water pipe system is first cut off, conveniently, in the case of a modern urban residential dwelling, at the water meter as by closing the main shut off valve in the house and then disconnecting the water meter. Cold water is drained from the pipe system through the source pipe or service pipe, in the case of the dwelling.

Although not necessary, it is preferable to isolate the hot water heater from the cold water pipe during a cleaning operation conducted in accordance with this invention. As many hot water heaters are simply cut off from the cold water pipe by a convenient existent valve arrangement, the isolation can often be simply accomplished. Preferably, the hot water heater is left filled with water.

To each faucet, cock, tap, valve, or the like, in the system for starting, stopping, or regulating water flow to the atmosphere from the system is preferably connected to a trap. This trap can be of any convenient and conventional form. Largely as a matter of convenience, I prefer to use plastic bags so formed that a bag mouth can be drawn tight around the discharge spigot of the faucet. Air holes formed in the bag wall near the faucet spigots so that when the spigot protrudes into the bag it is possible for air or gas to escape through the holes and for liquid to travel onward and be retained in the bag. In place of such plastic bags it is frequently convenient to use any convenient and readily available receptacle and simply to wrap cloths around the mouth of the spigot and the mouth of the receptacle when the spigot is positioned over the receptacle mouth, the cloth being left loose enough so as to permit the ready escape of air or gas. It is convenient to connect the cartridge 10 to the service pipe or source pipe which feeds water to an entire residence. Water meter hook-up spacing is an American Standard measurement, so that by making tube 14 of a

length suitable for fitting into the meter space, the cartridge 10 is readily connected to the system. When the tube 14 of the cartridge 10 replaces a water meter, either of two connections is possible. In one connection the cap 18 is left on the tube 14 and the valve 19 is directly connected to the source pipe 23. The arrangement shown on the drawings is suitable for connection to cast iron galvanized pipe. When copper tubing is involved, sweat fittings or the like can be used for joining the cartridge 10 to the source pipe 23. In the other connection the cap 18 is removed and a union is employed to connect the tube 14 to the service entrance, especially when there is a valve positioned between the water meter (in its normal position) and the entrance of the service pipe into the house or building. In this latter situation, when flushing

is desired at the close of a cleaning operation performed in accordance with the teachings of this invention, the valve in the service pipe is opened admitting fresh water to the system directly.

It will be appreciated by those skilled in the art, however, that in the cleaning of very large water delivery systems in accordance with the invention, the cleaning flushing operations can be introduced into any part of the system.

Usually, after the cylinder or cartridge 10 is connected to the source pipe 23 and valve 19 is closed between the cartridge 10 and the source pipe 23, a source of compressed gas is connected to the cartridge 10 through the

pipe 17. This source of compressed gas (which can be atmospheric air, carbon dioxide, nitrogen, or other inert gas) is usually available commercially in cylinders, one of which is herein designated by the numeral 24. Cylinder 24 is connected with the pipe 17 by means of tubing 25. Somewhere between the pipe 17 and the cylinder 24 is mounted a conventional reduction valve assembly 26 for controlling air pressure in cartridge 10.

The cartridge 10 functions as a reservoir. Those skilled in the art will appreciate that any apparatus which functions in a manner similar to that here described in relation to cartridge 10 can be used as a reservoir in the practice of this invention. The plug 11 is removed and reservoir of cartridge 10 is filled with a cleaning solution usually to the level of air inlet tube 17. Observe that the cartridge 10 is mounted so as to be in a generally upright position. After filling, the plug 11 is replaced and screwed tight. Pipe dope is conveniently applied to all screw fittings for sealing, water-tight engagements.

After the reservoir of cartridge 10 has been filled as described with cleaning solution, it is pressurized from the source of compressed gas. Usually the air pressure is from about 20 to 25 lbs. per square inch; although it will be appreciated that higher pressures can occasionally be employed expeditiously in particular use situations, depending on the type of pipe involved, joints, age, etc.

Depending upon the type of cleaning solution, it is next convenient to provide either one of two alternative procedures. If a cleaning solution is employed which is corrosive or destructive of the pipes themselves over long periods of time, such as when an acid is used to clean out hard water deposits in galvanized iron pipe, the following procedure is employed. The procedure is first to open all faucets and valves venting to the atmosphere and then admit pressurized cleaning solution to the water delivery system through the source pipe 23 from the reservoir of cartridge 10. In situations, the amount of cleaning solution employed is usually less than the volume of liquid which would be required to fill the entire cleaning system with solution in the absence of pressure and with the mouth of the source pipe 23 plugged or closed.

The alternative procedure if the cleaning solution employed is not particularly corrosive of the pipes involved, as is the case when commercial copper and brass cleaners are employed to cleanse copper pipes, is to admit the pressurized cleaning solution to the water system through the source pipe 23 from the reservoir of cartridge 10 with the faucets and valves venting to the atmosphere initially closed. Then, individually, each faucet and valve venting to the atmosphere is opened and the cleaning solution is permitted to vent from such opening until the cleaning solution sprays out of each such opening. The total amount of cleaning solution in this event is usually in volume approximately equal to that used in the previously described alternative procedure.

The next step involves optionally draining any residual cleaning solution from the system. This optional step can be used particularly when the cleaning solution does not contain strong acid or alkali harmful to the pipe system, so that such a draining step does not harmfully prolong contact of cleaning solution with pipe interiors. This is accomplished by conveniently opening a drain plug 20 of valve 19 and permitting any liquid in the source pipe 23 to drain outward into the atmosphere. When strong acids or alkalis are involved, they should be promptly neutralized or flushed from the system without taking the time to drain the system of such cleaning agents before proceeding to the next step.

Thereafter, the valve 19 is closed, and the next optional step of the invention can be performed. It is at this point that the reservoir of the cartridge 10 is filled with a flushing solution, for example, an acid neutralizer in the case where an acid has been used to clean pipes (i.e., galvanized iron pipes as described above). After the

reservoir of the cartridge 10 has been filled with liquid, it is pressurized from the source of compressed air.

Then, with the faucets and venting valves open, the pressurized flushing solution is admitted to the system through the source pipe 23 from the reservoir of the cartridge 10. It will be appreciated that this step of filling with flushing solution and flushing is optional and need not be employed in the practice of this invention.

The next step is to disconnect the reservoir of cartridge 10 and remove the traps from the faucets and valves and also to disconnect the source of compressed air from the cartridge 10 in an associated separate step.

Next, the cold water source is reconnected to the source pipe 23, as by reinserting the water (not shown) into the service line or source pipe 23. Finally, the pipes are flushed by allowing water to run through the system and by venting the water through the faucets and valves.

Those skilled in the art will appreciate that instead of using a cylinder of the design as described above, any similar cylinder accomplishing an equivalent result can be used. The main point is that the liquid in the cartridge 10 should be forced through small vents 16 so as to accomplish a breakdown of the liquid under the gas pressure and thereby produce a certain amount of atomization or degree of atomization in the cleaning solution entering the source pipe 23 and pipes of the water delivery system.

The invention is further illustrated by reference to the following examples:

(1) In a two-bedroom, contemporary home of approximately 1450 sq. ft., the plumbing system, which is constructed of galvanized cast iron pipe, is found to be contaminated with considerable corrosion and deposition of solid material from the local municipal water resulting in considerable diminution of water output from throughout the house. The house has 1½ baths, a kitchen and laundry tubs and a conventional gas fired hot water heating system.

As a first step, the water source is cut off using the shut-off valve located between the water meter and the basement wall, and the water meter is removed. All faucets and valves throughout the house are opened, and the hot water heater is isolated by closing the shut-off valve located above the tank and the cold water input line. A plastic trap, as described above, having a liquid holding capacity of about 1½ gallons is affixed to the spigot of each faucet. Next, the cartridge 10, having a capacity of about 1½ gallons, is positioned in the service line where the water meter was normally located. One end of the pipe 14 faces toward the input side (i.e., toward the basement wall) and is connected to that side by means of a union. The other end of pipe 14 is fitted with valve 19 and the valve 19 serves as a connecting union between pipe 14 and pipe 23 in the manner generally shown, for example, in FIG. 3. The source pipe 23 is a conventional 2" pipe.

With valve 19 closed, plug 11 is removed and the reservoir of the cartridge 10 is filled with muriatic acid. After the plug 11 is replaced and tightened, a cylinder of compressed air is connected to the gas inlet pipe 17 through valve 21. Valve 21 is now opened and the cartridge 10 is pressurized by 20 lbs. of compressed air. Next, valve 19 is opened. The action of the air on the acid forces the acid through the system and a chemical reaction then takes place and this reaction clears the pipe system of all corrosion and debris formed in the water pipe system. During the process of pressurizing the line the cold water faucets should be opened so as to vent the water system and allow the draining of the acid. When cartridge 10 is exhausted and after air, muriatic acid and spray have been allowed to vent from each faucet and valve venting to the atmosphere, the valves 19 and 21 are closed. Thereafter, the plug 11 is removed and the cartridge 10 is immediately filled with a soda solution formed by dissolving 1 lb. sodium bicarbonate and 2 gallons of water. The soda

solution flushes the system and neutralizes the muriatic acid. Then, the plug 11 is replaced and the cartridge 10 pressured as before with about 20 lbs. of compressed air. Next, the valve 19 is opened and the flushing solution is allowed to vent with compressed air and operate from each faucet and valve venting to the atmosphere.

Now, valve 21 is closed and the valve admitting municipal water is opened allowing tap water to flow through the pipe 14 so as to flush the entire system briefly with tap water. Finally, the line valve controlling input of tap water is again cutoff, and the cartridge 10 is removed and replaced with the water meter as before. Excellent tap water flow characteristics are observed at all faucets, spigots and valves venting to the atmosphere throughout the house. The residue obtained from the cleaning operation of the galvanized iron and steel piping consists of a heavy sludge with small pieces of rather hard material in chunky form.

(2) A home similar to that described in Example 1 but having a copper pipe system is observed to have similar difficulty in distribution of the water from the house input to and through all faucets and valves venting to the atmosphere. Following a procedure similar to that described in Example 1, a cartridge 10 having a $\frac{3}{4}$ " copper pipe 14, a mating valve 19, and a mating sweat fitting for coupling $\frac{3}{4}$ " copper pipe is connected in the source line in place of the water meter. Instead of muriatic acid there is employed a commercial copper and bronze cleaner containing oxalic acid. Here, before releasing pressurized cleaning solution from the cartridge 10, the faucets and valves venting to the atmosphere are closed. Then, following release of the pressured cleaning solution to the pipes, individual valves are opened and allowed to vent briefly cleaning solution, spray, and compressed air to the atmosphere. In this way the cleaning solution is allowed to remain in the piping system for a longer period of time which is not harmful to the pipes when a relatively non-corrosive cleaning solution is employed. The residue from the copper piping is of a greenish-black color, and the substance is assumed to be 40 copper oxide with a small amount of manganese which is present in most natural well waters. There is also observed a small amount of small particles of fine sand which presumably come from the source of water supply and which lay in the piping and are moved only by the application of air and solution. The residue is of a rather thin watery substance.

Next, after all of the liquid has been vented from the valves and faucets, the air pressure is cut off and the tap water supply source opened. Thereafter, water is intro-

duced into the system through all spigots and valves for a few minutes to flush the line. Observe no intermediate flushing operation is employed. Excellent tap water flow characteristics are observed at all faucets, spigots and valves venting to the atmosphere throughout the house.

5 Since the actual composition of the cleaning solutions used in the practice of this invention are conventional, such formulations are not described in detail herein.

10 My invention has been thoroughly tested and found to be completely satisfactory for the accomplishment of the above objects, and while I have shown and described a preferred embodiment, I wish it to be specifically understood that the same is capable of modification without departure from the spirit and scope of the appended claim.

15 What I claim is:

A casing having
 (a) an elongated outlet tube at its lower end which extends normal to the axis thereof and joined directly thereto, and
 (b) which communicates with the interior thereof through the medium of a plurality of longitudinally spaced apertures each having cross-sectional areas appreciably smaller than the cross-sectional area of said tube,
 (c) means at the upper end of said casing for introducing liquid thereinto,
 (d) independent means for introducing air under pressure into said casing above the fluid level thereof,
 (e) and means on one end of said outlet tube for detachably connecting same to a water pipe delivery system,
 (f) the opposite side portions of said casing converging to a width at the point of joinder thereof with said outlet tube less than the diameter of said outlet tube.
